FIRING PORT

Paul B. Tonnar, Cleveland, Ohio

Application August 8, 1932, Serial No. 627,922

6 Claims. (Cl. 263—15)

This invention relates to apparatus for burning fuel and more particularly to an adjustable firing port adapted to project combustible materials along with sufficient air into the refining chamber of a metallurgical furnace. The firing port herein disclosed and claimed in detail may be incorporated in the type of open hearth furnace disclosed in my co-pending application, Serial No. 629,249, filed August 17, 1932, wherein the same 10 is shown, but not claimed.

In the present day practice of operating metallurgical furnaces, and particularly open hearth furnaces, fuels and air are introduced into the refining chambers thereof through ports disposed 15 in the wall at one end of the furnace chamber and the products of combustion are conveyed from the furnace chamber through like ports in the opposite end wall of the furnace. The discharge ports, when the operation of the furnace is reversed, 20 constitute the ports through which the fuel and air are projected into the furnace. This reversal of the flow of hot gases along with the suspended matter carried thereby caused eroding of the furnace ports resulting in a continual change in 25 the effective area of the ports, with a subsequent change in the velocity and direction of the flow of gases into the furnace chamber. Furthermore, the lack of definite control of the flow of hot gases and the direction of the flame introduced 30 into the furnace chamber was not conducive of the most efficient operation of the furnace wherein it is desired to impart the maximum amount of heat to the charge disposed on the hearth of the furnace, obtainable from the amount 35 of fuel introduced thereto.

The illustrated embodiment of the invention comprises a firing port adapted to receive heated air from a flue and project the same along with the desired fuel, such as oil, tar gas or coke 40 oven gas, from an axially disposed fuel tube burner into the refining chamber of a furnace. The firing port is capable of relative movement with respect to both the flue and the furnace wall 45 and at the same time an effective seal is maintained between the firing port and both the flue and the furnace wall. The combustible mixture or flame may therefore be projected into the furnace at any angle which would be consistent 50 with the economical operation of the furnace or the system of firing employed therein. A more intimate and rapid uniting of air and fuel and the consequent more rapid and complete combustion is accomplished. The definite control of the direction and size of the flame and the resultant

effectiveness thereof is a further feature of my firing port.

Various advantageous features of this invention not at this time more particularly enumerated will become more apparent as the nature of the 80 invention is better understood from the following detailed description thereof, considered in conjunction with the accompanying drawings, wherein similar characters of reference designate similar parts and wherein:

Figure 1 is a sectional elevation of my firing port illustrating the relation thereof to the pre-heated air flue and furnace wall.

Figure 2 is a sectional view taken on the line 2—2 of Figure 1.

Figure 3 is an enlarged sectional view, partly broken away, illustrating the seal between the firing port and the preheated air flue.

Figure 4 is a sectional view illustrating the mounting of the firing port.

Figure 5 is a sectional view taken on the line 5—5 of Figure 4.

Referring now to Figures 1 and 2 of the drawings the illustrated embodiment of the invention comprises a firing port designated in its entirety by the numeral 1. The firing port 1 is supported on the sole plate of an air flue 2, which is preferably a cylindrical sheet metal conduit having a fire brick lining, and which conveys the preheated air from the regenerator chambers or 80 the recuperator (not shown) to the firing port through the central passage 3 thereof. Although the firing port as illustrated is supported on the top of the flue 2, installations thereof may necessitate the suspension thereof from an overhead 85 vertical flue or it may be mounted on and receive air from a horizontal flue and these modifications are deemed to be within the purview of this invention. The upper surface of the air flue 2 has slidably mounted thereon a circular casting 4. 95 The bottom face of the casting 4 which rests on the top surface of the air flue 2 is provided with an annular recess 5 which receives an upstanding annular flange 6 formed on the top surface of the sole plate which terminates the flue 2 and permits a limited amount of lateral movement 100 of casting 4 relative to the top of flue 2 to compensate for the lateral expansion or contraction of the furnace walls. A central passage 7 is formed in the casting 4 and co-operates with the 105 passage 3 in the flue 2 to conduct heated air from the latter to the firing port.

On the casting 4, adjacent the passage 7 and extending outwardly therefrom, a concave surface 8 is formed which receives the base casting 110

24 of the body portion of the firing port and will be referred to hereinafter more in detail. The casting 4 is preferably hollow to provide a chamber 9 through which cooling medium is adapted 5 to flow. Extending outwardly from the casting 4 is an annular flange 22 upon which is mounted a plurality of spaced bracket members 10 in which are journalled trunnions 11, the latter carrying rollers 12. The rollers 12 support a 10 circular plate or turntable 13 through a depending flange 14 which engages the trough formed on the periphery of the rollers.

Secured to the plate 13 are a pair of diametrically disposed bracket members 15 having trunnion bearings 16 formed integrally therewith in which are supported trunnions 17 and 17a. The trunnions 17 and 17a have formed on one end thereof a flanged portion 18 which is secured to the body portion 19 of the firing port in any suitable manner such as by welding or riveting. The body portion 19 is provided on the lower extremity thereof with an elliptical base casting 24 which is provided with a surface complementary to the surface 8 on the casting 4 to effect a seal between 20 these two members. The working surface on casting 24 is interrupted to form a continuous recess 40 adapted to contain a suitable packing or gasket 41. The packing 41 may be backed with a suitable leaf spring or analogous means 30 to insure its contact, at all times, with surface 8 on casting 4, thus effecting a further seal between members 4 and 24. Base casting 24 is also provided with a chamber 25 through which a cooling medium is adapted to flow.

35 The trunnions 17 and 17a are journalled in an eccentric member 23 carried by the bearings 16, and are provided with levers 23a. A set screw 18a extends through the cap of the bearing and engages the trunnion 17a. Adjustment of this 40 set screw permits the holding of the trunnions 17 and 17a in fixed rotational position relative to the bearings 16. The eccentric 23 is of such configuration that movement of the levers 23a in a direction away from the furnace will unseat the base 24 of the body portion of the firing port from the concave surface of the casting 4 and simultaneously therewith break the seal between a surface 31 formed on the firing port and surface 32 of a seat 33 located in the walls of the 45 furnace hereinafter referred to, thereby breaking the friction at the above mentioned points and thus permitting easy directional adjustment of the firing port. The annular plate 13 carries a depending cylindrical guard plate 20 which abuts 50 a sealing gasket 21 carried by the outwardly extending flange 22. An elliptical flexible member 13a is disposed between the ring 13 and the body portion 19 of the firing port to also exclude dust, or prevent the escape of air which might filter 55 through the joint between the base 24 and the surface 8.

The firing port 1 is preferably formed with a 60 nose portion 26 which when in operating position projects through an aperture 27 formed in a furnace wall 28. This nose portion 26 is preferably encased in a circular metal water cooled jacket 30 provided with a circular outwardly extending flange 30a. This flange is formed with 65 the concave surface 31 facing the furnace wall which co-acts with a complementary surface 32 formed on the water cooled seat 33 surrounding the aperture 27 adjacent the outermost portion thereof. When the surface 31 of the nose portion 70 is seated on the surface 32 an effective seal 75 is provided between the nose portion and the wall of the furnace.

Extending axially through the nose portion of the firing port is a fuel tube 35. This fuel tube is supported in a water cooled mounting 36 80 extending rearwardly from the body portion of the firing port. A ball and socket joint 37 is formed thereon to permit movement of the nozzle of the fuel tube 35 within the confines of the nose portion 26 of the firing port and independent of the adjustable movements of the firing port.

85 The fuel tube 35 is adapted to project liquid or gaseous fuels in the presence of or surrounded by preheated air conveyed to the firing port 1 90 through flue 3 into the furnace. Provision is made in the body of the tube or burner 35 to atomize the liquid fuel by means of air or steam.

95 It will be apparent from the foregoing description that I have provided a firing port which is capable of rotational and tilting movements with respect to its support and whereby it will be possible to project fuel and air into the furnace at any desired angle commensurate with the system of firing employed in the operation of the 100 furnace; furthermore that an effective seal is at all times maintained between the body portion of the firing port and the air flue and between the nose portion of the firing port and the furnace wall.

105 Although the foregoing description is necessarily of a detailed character to completely set forth this invention, I do not wish to be limited thereby other than by the appended claims.

I claim:

110 1. In a metallurgical furnace, in combination, an air flue, a furnace wall having an aperture therein, a hollow body member for projecting preheated air from said flue into the furnace having a nose portion which is encompassed by the wall of the aperture, said body member being given a tiltable and rotatable mounting whereby said nose portion may be adjusted at varying angles relative to said aperture, and means extended through said hollow body member and terminating near the discharge end thereof for projecting liquid fuel through said nose portion into the furnace, said fuel-projecting means being adjustable at varying angles within the confines of said nose portion.

115 2. In a metallurgical furnace, in combination, an air flue, a furnace wall having an aperture therein, a hollow body member for projecting preheated air from the flue into the furnace and having a nose portion which is encompassed by the wall of the aperture, said body member being given a tiltable and rotatable mounting whereby said nose portion may be adjusted at varying angles relative to said aperture, a fuel-projecting tube extended through said hollow 120 body member and terminating within the confines of said nose portion, and means for adjusting said tube at varying angles independently of said body member.

125 3. In a metallurgical furnace, in combination, an air flue, a furnace wall having an aperture therein, a hollow body member for projecting preheated air from said flue into the furnace having a nose portion which is encompassed by the wall of the aperture, said body member being given a tiltable and rotatable mounting whereby said nose portion may be adjusted at varying angles relative to said aperture, and an independently adjustable tubular fuel-projecting member extended through said body member 130

135 140 145 150

- and terminating adjacent the discharge end of the nose portion.
4. In a metallurgical furnace, in combination, a furnace wall having an aperture therethrough and a flue adapted to convey heated air, and a firing port provided with a base having a sealed universally movable connection with the wall of said flue and a nose portion which projects into and is encompassed by the wall of said aperture and has a universally movable sealed connection with said latter wall. 80
- 5 and a flue adapted to convey heated air, and a firing port provided with a base having a sealed universally movable connection with the wall of said flue and a nose portion which projects into and is encompassed by the wall of said aperture and has a universally movable sealed connection with said latter wall.
- 10 5. In a metallurgical furnace, in combination, a furnace wall having an aperture therethrough and a flue adapted to convey heated air, a firing port provided with a base having a sealed universally movable connection with the top wall of said flue and a nose portion which projects into
- 15 and has a universally movable sealed connection with said latter wall. 85
6. In an open hearth furnace, in combination, a furnace wall having an aperture therethrough, and a flue adapted to convey heated air, a firing port having its base communicating with said flue and a nose portion which projects into said aperture, a sealed rotatable and tilttable bearing connection between the base of said port and top wall of said flue, a sealed universally movable joint connection between said nose portion and the surrounding wall of the aperture, and means for tilting and rotating said firing port. 90
